UNITED STATES PATENT OFFICE

134,738

DESIGN FOR A PRINTING TELEGRAPH CABINET UNIT

Walter J. Zenner, Des Plaines, and Ralph A. Larsson, Chicago, Ill., assignors to Teletype Corporation, Chicago, Ill., a corporation of Delaware

Application June 18, 1941, Serial No. 101,530

Term of patent 14 years

To all whom it may concern:

Be it known that we, Walter J. Zenner and Ralph A. Larsson, citizens of the United States, residing at Des Plaines, in the county of Cook and State of Illinois, and at Chicago, in the county of Cook and State of Illinois, respectively, have invented a new, original, and ornamental Design for a Printing Telegraph Cabinet Unit, of which the following is a specification, reference being had to the accompanying drawings, forming part thereof.

Fig. 1 is a perspective view taken from the front of a printing telegraph cabinet unit showing the new design;

Fig. 2 is a plan view of the printing telegraph cabinet unit featuring the relative proportions of the component cabinets and their general arrangement; and

Fig. 3 is a side elevational view of the unit featured in Figs. 1 and 2 illustrating the continuous straight wall back portions.

We claim:

The ornamental design for a printing telegraph cabinet unit, substantially as shown.

WALTER J. ZENNER.
RALPH A. LARSSON.
